U.S. Cl. D6—175

FIG. 1

FIG. 2

FIG. 3

FIG. 4

FIG. 5

FIG. 1 is a perspective view of a table showing my new design;

FIG. 2 is a top view of the table as shown in FIG. 1;

FIG. 3 is a bottom view of the table as shown in FIG. 1;

FIG. 4 is a side view of the table, which is identical to all other side views since the table is symmetrical about a vertical axis through its center; and

FIG. 5 is a sectional view of the table taken in the plane represented by the line V—V in FIG. 4.

I claim:

The ornamental design for a table, as shown.
